ATTORNEYS.

UNITED STATES PATENT OFFICE

GEORGE AZONE, OF PHILADELPHIA, PENNSYLVANIA

AIR VENT FOR SIPHON FLUSH

Application filed October 6, 1928. Serial No. 310,702.

My invention relates to a new and useful air vent for siphon flush boxes of the siphon-jet type whereby the air pressure in the air pocket, formed between the level of the water 5 in the tank and in the toilet bowl, is relieved to facilitate the flow of water from said tank to said bowl, thereby increasing the force of pressure of the water and augmenting its cleansing capacity.

10 In certain conventional installations the water injected into the toilet bowl from the siphon flush tank is retarded in its downward flow with the result that a considerable amount of the force of the water is lost. This 15 is evidenced by the fact that the flow of water into and through the toilet bowl is at first rather slow and interrupted, the speed of the flow of the water increasing gradually, as the air in the air pocket formed in the pipe connecting the flush tank to the bowl is gradually released till a siphon effect is produced after 20 all of the air in said air pocket has escaped.

Since the ability of the water to clean the 25 toilet bowl depends primarily upon the force and speed with which the water flows, it is evident that by thus relieving the air pressure and permitting the unopposed, rapid flow of water to create a maximum siphon effect, a maximum efficiency is obtained, whereby the 30 necessity for manual cleaning of the toilet bowl is greatly reduced.

To the above ends, my invention consists 35 of a novel siphon flush box provided with an auxiliary air vent communicating with the air pocket referred to and leading to the atmosphere, whereby, when the water flows down through the main conduit, the air in said air pocket will escape through said air vent, thereby permitting the uninterrupted, 40 unretarded flow of water at full speed and with maximum force.

The invention consists of the novel construction hereinafter described and finally 45 claimed.

For the purpose of illustrating my invention I have shown in the accompanying drawings one form thereof which is at present preferred by me, since the same has been 50 found in practice to give satisfactory and reliable results, although it is to be understood

that the various instrumentalities of which my invention consists can be variously arranged and organized and that my invention is not limited to the precise arrangement and organization of the instrumentalities as herein shown and described. The figure represents a vertical section of an air vent embodying my invention.

Referring to the drawing, 1 designates an upper tank or reservoir having the bottom 2, 60 top 3, and sides 4. A water supply pipe 5 leads into the tank 1 and is provided with the valve 6, controlled by the float 7 through the arm 8 in the usual manner. 10 designates a pipe adapted to communicate with the supply pipe when the valve 6 is opened to fill the tank 1 with water after each flushing or emptying of the tank. 11 designates a gravity limb or discharge pipe extending downwardly through the bottom 2 of the tank into the 65 toilet bowl 12 and having its upper end connected to one end of an inverted U-shaped coupling 13, to the other end of which is connected the main siphon pipe 14 which is provided with the branch siphon pipe 15, 70 said pipes 15 and 14 being at an acute angle to each other. A relief pipe 16 connects the casing of the valve 6 with the upper end of the gravity discharge pipe 11 through the coupling 13, while an auxiliary pipe 17 provided with the nozzle 18, juxtaposed to the 75 lower end of the branch pipe 15, communicates at its other end with the valve 20 through the coupling 21.

In a flush box construction of the character 80 described, the air confined between the level of the water 23 in the main siphon pipe 14 and the level of the water 24 in the trap 25 forms an air cushion which retards the flow of water from the tank down through the pipe 11 into the trap 25 of the toilet bowl 12 when the closet is flushed. To allow the air thus 85 confined to escape and thus eliminate the resistance of the air cushion referred to, I provide the vent tube 26, the lower end 27 of which extends into the upper portion of the trap 25 above the water level therein, and the upper end 28 of which extends upwardly through the tank 1 above the level of the water 90 therein. By my novel construction, the 95 100

air confined in the pipe 11 and trap 25 escapes through the vent tube 26, thus producing a maximum siphon effect and allowing the water to flow uninterruptedly through the gravity pipe 11 and trap 25 through the port 27, with maximum force and speed, so that a quicker, more thorough and more efficient flushing of the toilet bowl is obtained.

It will be evident that my novel air vent 26 10 functions by balancing the air pressure within and without the discharge pipe 11 and trap 25 in the bowl 12. Thus, while the air pressure within the discharge pipe 11 and trap 25 may initially be equal to the normal 15 atmospheric pressure in the upper portion of the reservoir 1, it is evident that when water is first injected into said pipe 11, the air therein is confined in a pocket of gradually decreasing volume and a pressure results which 20 is in excess of the normal atmospheric pressure exerted in the upper portion of the tank 1, thus hindering or retarding the flow of water.

It is to be noted that while my novel air 25 vent is adapted for use in connection with a great variety of siphon flush boxes for toilet bowls, the accompanying drawing merely illustrates the application of my novel air vent to a siphon flush construction of the 30 character disclosed in my Patent No. 1,563,948, and to which reference can be had for a more detailed description of the siphon apparatus proper.

I am aware that the invention may be embodied in other specific forms without departing from the spirit or essential attributes thereof, and I therefore desire the present embodiment to be considered in all respects as 35 illustrative and not restrictive, reference being had to the appended claims rather than to the foregoing description to indicate the scope of the invention.

The discharge pipe 11 and the air vent tube 26, extending downwardly through the bottom 40 of the tank 1, are provided with the water tight joint 30 which comprises the sleeve 31 having the flange 32, the space between said pipes and said sleeve being filled with solder, plaster of Paris or any other suitable 45 water tight filler or packing 33. A gasket 34 is interposed between the flange 32 and the edge of the bottom wall 2 and the nut 35 is tightened around the lower threaded portion 50 36 of the sleeve 31 to assemble the joint.

Similarly, the lower ends of the pipe 11 and tube 26 are secured to the top of the toilet bowl 12 by the water tight joint 37 comprising the externally threaded sleeve 38, the gasket 39 and the nuts 40 and 41 which are tightened around the threaded sleeve 38, the space 55 between said pipes being filled with solder or any suitable water tight packing 42 as may be desired.

Having thus described my invention what

I claim as new and desire to secure by Letters Patent, is:—

1. A siphon flush for toilet bowls comprising a toilet bowl trap, a reservoir, a gravity discharge pipe leading from said reservoir into said trap, an air vent tube in proximity to said pipe and having its lower end in said trap above the water level therein and its upper end in said reservoir above the water level therein to permit the air confined in said discharge pipe and trap to escape through the upper end of said vent tube when said toilet bowl is flushed, and a single water tight joint for securing said pipe and tube to the bottom of said reservoir comprising a sleeve having a lower threaded portion extending through said bottom, a horizontally disposed flange for said sleeve engaging the upper surface of said bottom, a gasket for the underside of said flange, and a threaded nut engaging said lower threaded portion and bearing against the underside of said bottom, said pipe and tube being confined and guided in said sleeve. 70 75 80 85 90

2. A siphon flush for toilet bowls comprising a toilet bowl trap, a reservoir, a gravity discharge pipe leading from said reservoir into said trap, an air vent tube in proximity to said pipe and having its lower end in said trap above the water level therein and its upper end in said reservoir above the water level therein to permit the air confined in said discharge pipe and trap to escape through the upper end of said vent tube when said toilet bowl is flushed, a single water tight joint for securing said pipe and tube to the top of said toilet bowl trap comprising a threaded sleeve surrounding said pipe and tube and extending into said trap, a nut engaging the upper portion of said sleeve exterior of said trap, and a gasket intermediate said nut and the top of said trap, said pipe and tube being confined and guided in said sleeve. 95 100 105

3. In a siphon flush for toilet bowls, a toilet bowl trap, a reservoir, a gravity discharge pipe leading from said reservoir into said trap, an air vent tube having its lower end in said trap above the water level therein and its upper end in said reservoir above the water level therein to permit the air confined in said discharge pipe and trap to escape through the upper end of said vent tube when said toilet bowl is flushed, a water tight joint for securing said discharge pipe and air vent tube to the bottom of said reservoir comprising a sleeve surrounding said pipe and tube and having a lower threaded portion extending through the bottom of said reservoir, a horizontally disposed flange upon said sleeve arranged above the upper surface of said bottom, a gasket between the upper surface of said reservoir bottom and the underside of said flange, a threaded nut engaging the lower threaded portion of said sleeve and 110 115 120 125 130

bearing against the underside of the bottom
of said reservoir, a water tight joint for se-
curing said discharge pipe and air vent tube
to the top of said toilet bowl trap comprising
5 a threaded sleeve surrounding said pipe and
tube and extending into said trap, a nut en-
gaging the upper portion of said sleeve ex-
teriorly of said trap, and a gasket arranged
intermediate said nut and the top of said toi-
let bowl trap.
